UNITED STATES PATENT OFFICE.

JOSEF KURIG, OF ESSEN, GERMANY, ASSIGNOR TO FRIED. KRUPP, OF SAME PLACE.

LEVEL-QUADRANT FOR HIGH-ELEVATION GUNS.

SPECIFICATION forming part of Letters Patent No. 655,561, dated August 7, 1900.

Application filed May 17, 1900. Serial No. 16,962. (No model.)

To all whom it may concern:

Be it known that I, JOSEF KURIG, a citizen of the German Empire, residing at Essen-on-the-Ruhr, Germany, have invented certain new and useful Improvements in Level-Quadrants for High-Elevation Guns, of which the following is a specification.

This invention relates to improvements in level-quadrants for high-elevation guns, and has for its object to enable the gunner to adjust the gun to the proper elevation without the use of firing-tables.

It is well known that for all high-elevation guns powder charges of different weights are provided, so that according to distance a charge may be selected allowing the greatest possible elevation together with the greatest possible striking angle. The level-quadrants hitherto used consist simply of a spirit-level, which may be adjusted to different angles on a vertical graduated arc. In using such quadrants after the distance of the target has been ascertained the firing-table must first be consulted as to the proper powder charge for the desired striking angle and the corresponding elevation of the gun. Then only the level-quadrant may be set to the elevation thus determined and the gun pointed in the well-known manner.

The invention will be best understood by reference to the annexed drawings, in which—

Figure 1 is a front elevation, partly in section, showing the application of my invention to the class of level-quadrants hitherto used. Fig. 2 is an end view of Fig. 1, partly in section, seen from the right. Fig. 3 is a vertical section on the line III III, Fig. 1, seen from the left. Fig. 4 is a horizontal section on the line IV IV, Fig. 1, the level-casing being shown in top view. Fig. 5 is a section corresponding to Fig. 4, but showing some additional parts in top view. Fig. 6 is a horizontal section on the line VI VI, Fig. 1. Fig. 7 shows the distance-scale developed in a plane. Fig. 8 illustrates in front elevation my improvement as applied to a level-quadrant of a construction differing essentially from the one hitherto used. Fig. 9 is the corresponding end view from the left. Fig. 10 is a vertical section on the line X X, Fig. 8, viewed from the left. Fig. 11 is a section on the line

XI XI, Fig. 8, viewed in the direction of the arrow.

Similar letters and numerals of reference designate corresponding parts throughout the several views of the drawings.

Like the level-quadrants hitherto used, the instrument illustrated in Figs. 1 to 6 has an angular frame *a*, a graduated arc *b*, and a spirit-level *g*, the support *f* of which is arranged to turn on the center of the graduated arc in a plane parallel to the plane of the arc. The angle to which the level-support *f* is adjusted is read off on the graduated arc by means of a vernier *q*. The level-support *f* forms part of or is rigidly connected to a casing *e*, journaled on the frame *a* by pins *d*. The level is constructed to slide in ways *v* of its support *f*, whereby the angle of the level in relation to the casing *e* is changed. This angle is adjusted—that is, the level moved on the arc to the right or left—by a thumb-screw *t*, provided with a traveling nut engaging a socket in the bottom of the level, an index-hand on the level opposite a scale on the arched part of the support *f* indicating the angular change. The object of this arrangement is to eliminate the angle due to the difference of level between the gun and the target. The casing *e* contains a drum *m* and is closed at the outer right-hand end, Figs. 4 and 5, by a screw-plug *w*, from which a screw-shank *h* with a square left-hand thread projects and engages a corresponding internal thread of the drum *m*. A spindle *i* is journaled concentrically to the drum and has a square part *n*, which passes through a corresponding square hole in the bottom of the drum *m*. *k* is a button or hand-wheel for turning the spindle *i* and with it the drum *m*, which through its engagement with the screw-shank *h* is thereby moved in the direction of the axis. A pinion *l* is mounted on the shaft *i* and engages a toothed arc or rack *c* on the graduated arc *b*. *r* is a curved guard-plate secured to the frame *a* and provided with a slot *s*, through which the shaft *i* passes.

When the several parts described are in the relative positions shown in Figs. 1, 4, and 6 and the button *k* is turned to the right, the pinion *l*, rolling on the rack *c*, turns the drum-case *e*, together with the spirit-level *g* and

the vernier q , around the pins d , the shaft i being guided within the slot s . At the same time the square part n of the spindle i , engaging the bottom of the drum m , turns the latter to the right, whereby the drum is 5 screwed upon the fixed screw-shank h until it abuts against the plug w , each point of the drum traveling in a screw-line determined by the direction and pitch of the thread on the shank h . The parts are so proportioned that when the pinion reaches the outer end of the rack c —that is, when the level has reached the highest angular position on the quadrant—the drum m abuts against the plug w , 10 thereby preventing further motion of the drum-case and of the level-support. A suitable number of windows p' to p^6 are provided in the top part of the casing e with index-marks o' to o^6 , and upon the outer cylindrical surface of the drum a corresponding number of graduation-marks are placed, which are arranged on a left-hand spiral of the same pitch as the screw-thread of the shank h . In the position of the drum m shown in Fig. 5 the zero-points of these spirals are opposite the marks o' to o^6 . By this arrangement of the drum the turning of the button k causes each scale to pass along the mark on its window. The number of windows and scales is governed by the number of different weights of powder charge, one window and scale being provided for each weight. Fig. 7 shows a development of the spiral graduation on a larger scale, the divisions being so made that when the level 15 is set to a certain angle of elevation the index-marks on the windows will point out the distance in meters at which, with the corresponding powder charge, the projectile will hit the target when the gun is elevated to the angle of the level. Assuming, for example, that the window p' is arranged for a charge of four hundred grams, window p^2 for three hundred and fifty, and each succeeding window for fifty grams less, and further assuming that at an elevation of thirty degrees and a charge of four hundred grams, the gun will have a range of five thousand millimeters, and with a charge of three hundred and fifty 20 grams a range of four thousand four hundred millimeters. Then when the level is set to thirty degrees the number of "5000" must appear at o' and "4400" at o^2 .

The improved instrument is used as follows 25 when firing from howitzers: Taking it for granted that for obtaining a proper angle of descent or of striking, which angle, as is well known, always is somewhat larger than the elevation of the gun, the latter should be at least thirty degrees, the level of the quadrant is set to thirty degrees by turning the knob k . Then the number nearest to the required range is looked up on the scales beneath the windows, when the corresponding window 30 will indicate the powder charge to be used. The position of the level is then corrected to the proper angle by turning the knob k until

the fixed index at the window for the proper charge points to the required range. Another way of proceeding is to turn the knob k until the required range appears at the window for the charge assumed from experience to be the proper one. If then the angle shown on the quadrant is not at least thirty degrees, the assumed charge is too heavy, and the quadrant must be set for a smaller charge and the required range. After the level has been adjusted to the proper angle by one of the methods the gun is turned to the proper angle in the well-known manner. To guard 35 against errors in adjusting for a distance and to be able to conveniently assure correct adjustment, a sliding index may be provided on the drum-case, which is set to the window corresponding to the selected powder charge, 40 or all the windows but the one might be shut.

When the dimensions of the pinion l are so taken that it passes over the whole of the rack c at a single revolution or a part of one revolution, the graduations on the drum, m 45 need not be on a spiral, but may be on annular zones, and no spiral motion of the drum, but only rotation of the same, would be required. Such an arrangement, however, while practicable for the usual construction 50 of level-quadrants, as shown in Figs. 1 to 6, would not constitute a convenient instrument, owing to the necessarily-large diameter of the drum m .

In Figs. 8 to 11 I have shown a level-quadrant with a rotary drum without axial motion and which is not an adaptation of the construction of the level-quadrant hitherto used to the present purposes. The quadrant-frame 1 is formed with concave ways 2 for the level-support 3. The spirit-level 16 is guided in ways of the support 3, curved to the arc of a circle, so that the angle due to the difference of level may be eliminated in the usual manner by turning the screw 6. 55 The frame has a hollow gudgeon 22, on which the drum 8 turns without having axial motion, which motion is prevented by the pins 9, screwed into the rim of the hollow gudgeon and projecting into an annular groove 10 of the drum. The drum 8 has a milled raised border 11 for adjusting it by hand, and gear-teeth 12, engaged by a pinion 13 at one end of a shaft 14, which is journaled on the frame 1. At the opposite end of the shaft is a worm 15, engaging suitable teeth 25 on the lower side of the level-support 3. By turning the drum 8 the level-support 3, together with the level 16, is turned on the concave ways 2. Upon the outer cylindrical surface of the drum 8 are six annular scales $5'$ to 5^6 , and to the frame is secured an attachment 17 18, the part 17 of which partly surrounds the drum, while the part 18 serves as a guard for the pinion 13. One of the scales $5'$ to 5^6 (by preference 5^6) is provided with a graduation and on the part 17 of the attachment is a horizontal index 26. The graduation 5^6 is such as to always indicate the angle at which the level

and its support have been turned by turning the drum, for which reason no graduation and no index are required on the frame 1 and the level-support 3. The scales 5' to 5⁵ have distance-divisions in meters and as to number and division are arranged like the scales above described in relation to Figs. 1 to 6. To be enabled to set the drum to the powder charge selected and to the distance of the target, a window 20 is arranged to slide in a horizontal slot of the part 17 of the attachment. The window can be adjusted to any one of the scales 5' to 5⁵ for different powder charges by means of an index 21 thereon and marks 7' to 7⁵ and is clamped by a nut 23. The respective distance for which the drum is set is then read off at the horizontal index 19 of the window. When using the instrument, the window 20, with its vertical index 21, is adjusted to the mark for the powder charge selected—for instance, 7⁴ on the part 17. The drum 8 is then turned by hand until the division of the scale (in this case 5⁴) corresponding to the distance of the target is opposite the horizontal index 19. The level has then the elevation required for the distance and powder charge. In the usual manner the gun is then raised to the proper elevation after eventually the angle due to the difference of level of gun and target has first been taken care of by turning the screw-spline 6.

What I claim as new is—

1. A level-quadrant for high-elevation guns containing a rotatable drum carrying on its periphery a plurality of scales and positive

means for making the angular motion of the drum proportional to the angular motion indicated by the quadrant, substantially as described.

2. In combination with the frame of a level-quadrant for high-elevation guns; a level and its support adjustable to different angles in the frame; a scale and index showing the angle to which the level-support is adjusted; a rotatable drum carrying on its surface a plurality of scales, each scale showing by an index the range for a special powder charge at different elevations of the gun, the movable parts connected for equal or proportional relative angular motion between the scales and their indices, substantially as described.

3. In combination with the frame of a level-quadrant for high-elevation guns; a level and its support adjustable to different angles in the frame; a scale and index showing the angle to which the level-support is adjusted; a rotatable drum carrying on its surface a plurality of spiral scales, each scale showing by an index the range for a special powder charge at different elevations of the gun, the movable parts connected for equal or proportional relative angular motion between the scales and their indices, substantially as described.

In testimony whereof I have hereunto set my hand in the presence of two subscribing witnesses.

JOSEF KURIG.
